UNITED STATES PATENT OFFICE.

WILLIAM STEPHENSON, OF ST. LOUIS PARK, MINNESOTA.
SEEDER.

SPECIFICATION forming part of Letters Patent No. 701,642, dated June 3, 1902.
Application filed November 9, 1901. Serial No. 81,683. (No model.)

To all whom it may concern:

Be it known that I, WILLIAM STEPHENSON, a citizen of the Dominion of Canada, residing at St. Louis Park, Hennepin county, Minnesota, have invented certain new and useful Improvements in Seeders, of which the following is a specification.

The invention relates to seeders, and particularly those of the disk type.

10 The object of the invention is to simplify the construction and reduce the weight of the ordinary seeder-frame and provide a clear open space beneath the hopper for the feed-spouts and their connections by dispensing 15 with the usual wheel-axle.

A further object is to provide means for adjusting the wheel-spindles to alter their pitch or inclination with respect to the hopper.

20 A further object is to improve the method of gearing the feed-shaft to the wheels and for rendering said gears operative or inoperative.

25 A further object is to provide improved means for oiling the gears and axle-spindles. The invention consists generally in various constructions and combinations, all as hereinafter described, and particularly pointed out in the claims.

30 In the accompanying drawings, forming part of this specification, Figure 1 is an end view, with the bearing-wheel removed, of a seeder-frame embodying my invention. Figs. 2 and 3 are details of the gear mechanism.

35 Fig. 4 is a section on the line $x-x$ of Fig. 2. Fig. 5 is a detail section of the frame, showing the manner of securing the axle-spindle thereto. Fig. 6 is a section on the line $y-y$ of Fig. 5. Fig. 7 is a section showing the gear-operating crank on the rock-shaft. Fig. 8 is an end view of the hopper and the seeder-gearing. Fig. 9 is a section on the line $z-z$ of Fig. 8.

40 In the drawings, which represent a seeder of the disk type, I have shown a frame 2 of angle-bars having a suitable pole 3 and a series of disk draw-bars 4, pivotally connected with the frame and provided with castings 5, whereon the disks 6 are mounted. Each casting is provided with a rod 7, pivotally connected thereto and slideable in a swivel 8 on an arm 9, that is secured to the rock-shaft 10. A

cotter-pin 11 prevents disengagement of the rod 7 from said swivel, and a spring 12 on said rod is compressed by the downward movement of said frame, all of which is common to seeders of this class. Upon the frame 2 are brackets or standards 13, supporting a hopper 14 of the usual form.

45 In seeders as usually constructed the axle 60 extends through the frame beneath the hopper and interferes to a considerable extent with the feed mechanism, rendering it necessary to place the feed-spouts usually at the front of the hopper when more properly they should be located at the back thereof.

In my improved seeder I have dispensed entirely with the axle and have provided holes 15 in the vertical flanges at the ends of the seeder-frame to receive axle-spindles 16, that are provided with depending flanges 17, secured to said vertical flanges by bolts 18, and with ears 19, that are preferably secured to the horizontal flanges of said frame by suitable bolts 20, that pass through said ears, said flanges, and the legs of the standards 13, securely binding them together. The flanges 17 are braced by the ears 19 and have a rigid support in the angle-bar of which the frame is composed. This method of securing the axle-spindles to the frame of the seeder permits me to adjust them to vary the angle of inclination of the bearing-wheels with respect to the hopper. I can either cause the wheels to run on a plumb spoke or adjust the wheels so that the spokes will be slightly inclined. I prefer, however, to have the spokes substantially plumb, as I have found that the wheels are inclined either toward or away from the hopper the seeder will run harder particularly in soft ground, and that when inclined toward the hopper the mud taken up by the wheels is apt to lodge between the ends of the hopper and the wheel-spindles the broken part can be removed and a new spindle substituted thereof.

50 The hubs 21 of the bearing-wheels are provided with a gear 22, secured between the side rail of the frame 2 and the feed-shaft 24 is provided with whose hub 26 slides on the square shaft, and turning loosely upon said

means for changing the angle of said spindles with respect to said frame, for the purpose specified.

10. In a seeder, the combination, with a wheel-hub having a gear, of a feed-shaft provided with a gear and located above said wheel-hub gear, an oil-tube, a lever provided with a sleeve loosely mounted on the hub of said feed-gear and having a hole communicating with said oil-tube, and an idle gear carried by said lever and adapted to engage said wheel-hub gear and said feed-gear.

11. The combination, in a seeder, of the bracket 13 provided with an oil-tube 31', a feed-shaft below said oil-tube, a gear having a hub slidable on said shaft, a lever having a sleeve adapted to rotate on said hub, said hub and sleeve having oil-holes registering with the discharge end of said oil-tube, a driving-gear, and an idle gear provided on said lever and adapted to engage said driving-gear and said feed-gear.

12. In a seeder, the combination, with the frame and the wheels supporting the same, of a driving-gear provided on one of the wheel-

hubs, a feed-shaft above said driving-wheel, a feed-gear having a hub slidable on said shaft, a lever provided with a sleeve loosely mounted on said hub, an idle gear slidably supported on said lever and adapted to engage said driving-gear and said feed-gear, and a guard 32' provided over said feed and idle gears and between them and said wheel and limiting their outward sliding movement, substantially as described and for the purpose 35 specified.

13. The combination, with an axle-spindle, of the wheel-hub provided with a gear, a feed-shaft also having a gear, a lever loosely mounted on said feed-shaft, a gear mounted on said 40 lever and adapted to engage said axle and said feed-shaft gear, a rock-shaft, and a yielding connection provided between said lever and said rock-shaft.

In witness whereof I have hereunto set my hand this 28th day of October, 1901.

WILLIAM STEPHENSON.

In presence of—

RICHARD PAUL,
M. C. NOONAN.
